UNITED STATES PATENT OFFICE.

SAM P. SMITH, OF CABOT, ARKANSAS.

AUTOMATIC RAILWAY-CROSSING SIGNAL AND BAR.

Application filed July 11, 1924. Serial No. 725,468.

One object of my said invention is the provision of an automatic apparatus controlled by an approaching train and adapted when a train reaches a point in proximity to a railway crossing to signal the approach of the train at the crossing, the signal element being adapted after the train has traversed the crossing to return to idle position.

Another object of the invention is the provision of an apparatus of the kind indicated in which the signal member is utilized to constitute a bar at the crossing.

Other objects and practical advantages of the invention will be fully understood from the following description and claim when the same are read in connection with the drawings, accompanying and forming part of this specification, in which:—

Figure 1 is an elevation illustrating the arrangement of the preferred embodiment of my invention relative to a railway and a crossing transfer.

Figure 2 is an enlarged detail view illustrating the motor of my improvement and means for establishing and interrupting connection between the said motor and the movable signal member of my improvement.

Figure 3 is an enlarged detail section taken in the plane indicated by the line 3—3 of Figure 1.

Figure 4 is an enlarged detail section showing the stop for the movable signal member.

Figure 5 is a diagrammatic view illustrative of the electric connections employed in the preferred embodiment of my invention.

Similar numerals of reference designate corresponding parts in all of the views of the drawings.

In Figure 1, I show a railway 1 intersected by a crossing 2 and at opposite sides of the crossing 2 I arrange uprights 3, upon which is supported a roof 4, Figures 1 and 3. The said roof 4 is inclined in the direction of its length as is also a drag rod 5 disposed under and in parallelism to the roof 5 and interposed between and supported by the uprights 3.

At 6, I illustrate a signal member, equipped at 7 with wheels journaled between the forked upper end of spaced arms and arranged and adapted to travel on the rod 5. The said signal member may be of any type compatible with the broad purpose of my invention, though I prefer to have it comprise

a body arranged in a frame which has its end portions secured to the arms and said body 7 bears an appropriate legend such as the word "Stop" indicated by 8, and spaced rods 9 are connected to and depend from the body 6 as shown. Manifestly when the signal member 6 is characterized as stated, the said signal member 6 when positioned as shown in full lines in Figure 1 will serve as a signal and also as a bar calculated to discourage persons from attempting to cross the railway 1. When the signal member 6 is moved to the said position shown in Figure 1, said member 6 will bring up against and will be stopped by the stop member 9 which is shown in Figure 4 as being adjustably fixed by a set screw 10 to the rod 5. When the signal member 6 after being moved to the position shown by full lines in Figure 1 is released the said signal member will gravitate to the idle position shown by dotted lines in Figure 1.

Appropriately supported as by one of the uprights 3 is a casing 11, Figures 1 and 2, and in the said casing 11 is arranged an electric motor 12, Figures 2 and 5, the said motor 12 being of any construction or type compatible with the purpose of my invention. The armature shaft of the motor 12 is connected by gearing 13 with a shaft 14 on which is arranged a friction disk 15, the said disk 15 being mounted to turn with the shaft 14 and to move in the direction of the length of the said shaft 14. The said shaft 14 also carries a fly wheel 16, and centrifugal governor weights 17, the said weights being carried by spring arms or strips 18 which are connected at 19 to the fly wheel 16 or to an appropriate member of the shaft 14, and are connected at 20 to the hub of the friction disk 15. The motor 12 is shown in Figure 5 as arranged in a normally open electric circuit which includes not only the motor 12, but incandescent electric lamp 21, a source of electric energy 22, and rail sections 23 and 24 arranged in a block insulated at 25 from the remainder of the rails. The block alluded to will be located at an appropriate distance from the crossing, and hence when no train is in the block the signal member 6 will rest in the idle position shown by dotted lines in Figure 1. When, however, a train is in the block as designated by 26 in Figure 2, the electric circuit will be completed through the wheels and an axle of the train as shown in Figure 5, and hence the

motor 12 will be energized for the rotation of the shaft 14 and the friction disk 15. As soon as the train represented passes out of the block referred to the motor 12 will be de-
5 energized. The lamp 21 is shown in Figure 1 as carried on one of the uprights 3 and as disposed and provided with a reflector 22 so as to illuminate the signal member 6 when said member 6 is in working position. From
10 this it follows that my novel signal will serve efficiently in the night time as well as in the day time.

Connected at 30 to the signal member 6 is a cable 31 that is carried through an opening 32 into the casing 11, and is connected to and adapted to be wound upon a drum 33 mounted to rotate in appropriate bearings in the casing 11 and fixed with respect to a fly wheel 34 and a friction disk 35, the
20 latter being disposed at right angles to the disk 15 and being preferably arranged in the relation illustrated thereto. From this it follows that when the electric motor is energized as before stated and the shaft 14 is rotated, the centrifugal means described will operate to move the friction disk 15 into engagement with the friction disk 35, whereupon the cable 31 will be taken up on the drum 33 and the signal member 6 will
25 be moved from the position shown by dotted lines in Figure 1, to the position shown by full lines in said figure. When the signal member 6 brings up against the stop member 9 the frictional contact between the disk 15 and the disk 35 will serve to retain the signal member 6 in said position, and this notwithstanding the disk 15 will slip against the disk 35. On deenergization of the motor 12 the spring arms or strips 18 will thrust the disk 15 out of engagement with the disk 35, whereupon the signal member 6 will gravitate and travel from the position shown by full lines in Figure 1 to the idle position
30 shown by dotted lines in said figure.
40 It will be apparent from the foregoing that my novel signal is reliable in operation, and is entirely automatic and under the control of a train approaching the crossing, the presence of the train on the block being

always attended by the movement of the 50 signal member 6 in the position shown by full lines in Figure 1 and the passage of the train from the block being always followed by the movement of the signal member 6 from the full line position shown in Figure 55 1 to the dotted line position.

I have specifically described the preferred embodiment of my invention in order to impart an exact understanding of said embodiment and all of its details. I do not 60 desire, however, to be understood as confining myself to the specific construction and relative arrangement of parts as set forth inasmuch as my invention is defined by my appended claim, and within the scope of the 65 said claim changes or modifications may be made without involving departure from my invention.

Having described my invention, what I claim and desire to secure by Letters-Patent, 70 is:

In a crossing safety device, the combination of uprights arranged at opposite sides of a crossing, a drag rod secured between said uprights at their upper ends, a gravitational signal member movable on said rod in the direction of the length thereof and to and from a position in coincidence with the crossing, said signal member including a frame, a body mounted in said frame, arms having forked upper ends and having their lower ends secured to the opposite portions of said frame, wheels journaled in the forked ends of said arms and mounted on said rod, a stop on the rod for limiting the movement of the member in one direction, means controlled by a train approaching the crossing for actuating said means for moving said member against the action of gravity and to operative position against said stop, illuminating means carried by one upright in confronting relation with said signal only when the latter is in its operative position and being illuminated when said signal is in said position.

In testimony whereof I affix my signature,

SAM P. SMITH.
